CLAIM

The ornamental design for a extension for partition bracket, as shown and described.

DESCRIPTION

FIG. 1 is a perspective view of a extension for partition bracket showing the new design;

FIG. 2 is a front elevational view of the extension for partition bracket shown in FIG. 1;

FIG. 3 is a left, side elevational view of the extension for partition bracket shown in FIG. 1 (the right, side elevational view of the extension for partition bracket is a mirror image of the view shown in FIG. 3);

FIG. 4 is a rear elevational view of the extension for partition bracket shown in FIG. 1;

FIG. 5 is a top view of the extension for partition bracket shown in FIG. 1; and,

FIG. 6 is a bottom view of the extension for partition bracket shown in FIG. 1.
